Leo J. Wahl.

Atty-

UNITED STATES PATENT OFFICE.

LEO J. WAHL, OF STERLING, ILLINOIS.

CLIPPER.

Application filed January 29, 1925. Serial No. 5,502.

- My invention relates primarily to clippers intended for use in barber shops and in which the clipper is provided with a handle portion, by means of which it may be used, a cable or cord being provided and extending from a suitable source of current supply to the handle portion, means also being provided for switching on or off the operating current.
- 10 One object of my invention is to provide a suitable switch for the current and to locate the operating portion of the switch outside of the handle portion of the clipper and adjacent the point of entry of the current supply cable, to the end that when the clipper is in operation the switch operating device will be in such a position as to not interfere with the proper handling and use of the clipper.
- 15 Other objects of my invention will appear and be described in the specification.
- The novelty of my invention will be hereinafter more fully set forth and specifically pointed out in the claims.
- 20 In the accompanying drawing:
- Fig. 1 is a plan view of a clipper embodying my invention, the cover of the case or handle being removed.
- Fig. 2 is a detail of a part of the mechanism of the switch.
- The same numerals of reference are used to indicate identical parts in both figures.
- As illustrating one form of construction embodying my present invention, though without limiting myself to the precise details of construction or arrangement of parts shown, but availing myself of all modifications and equivalents which may be made or used within the scope of the appended claims, I have shown a clipper comprising a case or handle 1 within which a suitable core 2 is mounted, the core carrying a coil 3 properly wound to magnetize the core when current is supplied to the coil. The coil is connected at one of its terminals by a lead 4 with a switch which consists of an insulating base 5 one face of which is provided with a plurality of cams, or inclined projections 6, there being preferably four of such projections two of which, at opposite sides of the base 5 are covered with contact pieces 7 and 8, the lead 9 being connected with contact piece 8. The other terminal of the coil is connected through lead 10 directly to the source of current supply, to which the lead 9 also extends.
- The movable contact of the switch is shown more clearly in Fig. 2 and consists of a pair of angularly arranged feet 11 attached as by legs 12 to a disc 13 which has a square opening through it as clearly shown in Fig. 2. Referring again to Fig. 1 the disc 13 engages the square of a shaft 14, the latter carrying a collar 15, between which and the disc 13 a spring 16 is mounted to normally press the contact feet 11 into engagement with one or the other of the inclined surfaces 6.
- The shaft 14 projects through the end of the case 1 and carries an operating knob 17 by means of which it may be turned.
- The construction just described produces a switch in which the contact is made or broken with a snap to prevent arcing and consequent destruction of the contact members, it being noted that as the shaft 14 is turned, the contact feet 11 ride up the inclined projections and as they pass the ends thereof, are snapped into engagement with the next inclined surface. The spring 16 causes the action of the contact portion of the switch along the squared portion of the shaft 14.
- It is to be noted that the operating knob 17 is located at the end of the handle and beside the cables 9 and 10, to the end that while the clipper is being used both the cables and the operating knob 17 will be out of the way of the operator's hand and in addition, by placing the switch in the handle of the clipper, it is not necessary for the operator to reach for a lamp socket or other switch to start or stop the operation of the clipper, thus making a very convenient and efficient machine.
- Any suitable armature 18 may be mounted in the case 1 and be located adjacent of the pole pieces of the core 2, to be operated by the magnetism produced by the operating current, the armature being connected to operate the movable clipper blade 19 which cooperates with the stationary clipper blade 20 carried by the case or handle 1. In addition any suitable tuning screw 21 may be employed to properly tension the armature carrying spring 22.
- Having thus fully described my invention, I claim:
1. In a clipper the combination of a handle or frame member, a stationary clipper

blade mounted at one end of the handle, a movable clipper blade cooperating with the stationary blade, electrical blade moving mechanism, current supply leads entering the handle and for supplying current to the blade moving mechanism, a current switch within the handle, and switch operating means extending outside the handle adjacent the point of entry of the current supply leads.

2. In a clipper the combination of an elongated handle portion, clipper blades at one end thereof, electrical mechanism in the handle for moving one of the clipper blades, current supply leads entering the handle at the opposite end from that which carries the clipper blades, a current switch in the

handle, switch operating mechanism extending through the end of the handle adjacent the point of entry of the current supply leads. 20

3. In a clipper the combination of an elongated handle, clipper blades carried at one end thereof, electrical mechanism in the handle for operating one of the blades, a rotating switch in the handle, current supply leads entering the handle at the end opposite from that which carries the blades, a switch operating shaft extending through the handle and a turn button on the switch shaft 25 and outside the handle and adjacent the point of entry of the current supply leads. 30

LEO J. WAHL.
